SCREW HOLDING SCREW DRIVER

Albert L. Stanelle, Milwaukee, Wis.

Application February 4, 1949, Serial No. 74,510

1 Claim. (Cl. 145—50)

1

My invention relates to screw drivers and more particularly to a type of screw driver that will retain contact with the screw.

An object of my invention is to construct a screw driver that will provide frictional resistance with the vertical walls of the slot in a screw head, thereby permitting the operator to place the screw on the screw driver and in position in "hard to get at" places.

Another object of my invention is to construct the head of a screw driver in a manner to provide resiliency at all times so that the contact points or blades are urged apart from one another.

Still another object of my invention is to construct a screw driver head in which the contact blades may be easily inserted into the slot or grooves of a screw head.

A still further object of my invention is to construct a device of the character described that is practical, economical to manufacture and is efficient for the purpose for which it is intended.

It is manifest to anyone familiar with the art of using screw drivers that it is sometimes difficult to place a small screw or bolt in position, and it is therefore advantageous to support the screw by means of a screw driver when placing the screw into a remote corner or position in a congested assembly. With the device as described it is a simple task to insert the blades of the screw driver head into a slot of a screw and retain the screw in position on the screw driver head by means of frictional contact of the blades with the vertical walls of the slot, thereby eliminating the necessity of any mechanical accessories on the screw driver for retaining the screw onto the head.

Other and further objects of my invention more apparent as the description proceeds and when taken in conjunction with the drawings in which

Figure 1 is a perspective side view of the assembled screw driver.

Figure 2 is a side view of the head of the screw driver as shown in Figure 1.

Figure 3 is a front view of the head of a screw driver as shown in Figure 2.

Figure 4 is a fragmentary perspective view of a screw driver head and screw, illustrating the manner employed to insert the blades into the slot of a screw, and

Figure 5 is a fragmentary view of the blades of the screw driver head inserted into the slot of the screw.

2

Similar characters of reference indicate corresponding parts throughout the several views, and referring now to the same, the character 10 shows a screw driver stem provided with a conventional type of handle 11 fastened in any serviceable manner.

The depending end of the stem 10 terminates into a head which consists of an annular portion 12 having an aperture 13 extending through its entire cross-section. The lower end of the annular portion 12 extends outward to form two blades shown as 14 and 14' and shown separated from one another by means of a slot or space 15 extending from the extreme outer end of the blade 14 to the aperture 13. The outer peripheral surface of the annular portion 12 terminates into an arcuate contour shown as 16 at the junction with the blades 14 and 14', thereby providing resiliency for the blades.

Obviously, the length of the blades or their cross-section, or the diameter of the slot 15 may vary to suit the particular type of screw driver and the purpose for which it is intended.

The slot 15 provides a space between the blades 14 and 14' and the arcuate construction of the head supporting the blade provides a means of urging the blades away from one another to a distance equivalent to the width of the slot.

When the tips or extreme ends of the blades 14 are inserted into a slot 17 in the screw shown as 18 in Figures 4 and 5, the outside diameter of the spread blades being greater than the width of the slot 17 will cause the blades 14 and 14' to be forced toward one another, thereby narrowing the diameter of the slot or space 15 between the blades and causing the outer surface of the blades to frictionally engage the vertical walls of the slot 17 in the screw.

The arcuate contour and construction of the head provides resiliency to cause the spreading inclination of the blades.

In Figure 4 I illustrate the manner employed for engaging the blades 14 and 14' into the slot 17. By forcing the blade 14' against the shoulder of the slot 17 in the screw, it will cause the space 15 to narrow, thereby permitting the other blade 14 to enter the slot 17 when the screw driver head is brought into alignment with the screw shown as 18.

In the chosen embodiments of my invention there are present many features not heretofore disclosed in the prior art, and although I have shown a specific construction and specific contour and arrangement, I am fully cognizant of the fact that many changes may be made with-

out affecting their operativeness, and without departing from the spirit of my invention or the scope of the appended claim.

Having thus described my invention, what I claim and desire to secure by Letters Patent in the United States is:

A device of the character described, said device being fabricated of a single piece of material shaped to define an elongated cylindrical stem, one end of said stem including a head, said head being flattened and enlarged and being provided with a centrally disposed aperture, said head having a pair of outwardly extending, resilient blades spaced parallel to each other and spaced apart from one another defining a slot extending from said aperture to the ends of said blades, said slot being arranged in alignment with the longitudinal axis of said stem, said blades being mounted for movement toward and away from each other, the outer periphery of said head extending outwardly and arcuately so that there is provided a gradual diminishing of the cross-sectional area of the head terminating

in said blades, the distance from the aperture to the outer edges of the head being greater than the thickness of the major portions of the blades, the longitudinal axis of said aperture being arranged at right angles to the longitudinal axis of said slot.

ALBERT L. STANELLE.
